UNITED STATES PATENT OFFICE

HEINRICH REICHMANN, OF DUISBURG-RUHRORT, GERMANY

AUTOMATIC GRAB

Application filed February 25, 1931, Serial No. 518,176, and in Germany February 28, 1930.

This invention relates to an automatic grab in which the buckets are linked on a rigid pulley box to pressure bars. In all known bucket grabs the grab buckets which are linked on a pulley box to pressure bars are provided with a second pivot and are suspended in such a manner that the buckets, on the grab opening and closing, must always move positively in dependence on one another, even in grabs in which the grab buckets are displaced laterally for increasing the span of the jaws. The grab buckets of the known systems cannot therefore penetrate independently of one another more or less deeply into the material to be dealt with according to the resistance of the latter.

In contradistinction thereto, according to the invention the grab buckets are provided instead of with the internal pivot with bucket arms which are rigidly connected to them, extend into the pulley box and are capable of moving in the pulley box independently of one another. By this means each of the buckets can swing independently about its one pivot and adapt itself, independently of the other bucket, to resistance which it happens to strike when entering the material to be grabbed.

Preferably the grab arms are guided in sliding paths provided on the pulley box, the main function of which is to enable the grab buckets to open uniformly, the positive opening of the grab being ensured by the discharge ropes forming a pulley block arrangement between the end of the bucket arms and a point on the pulley box.

Such a grab is particularly suitable for unloading sea-going and river craft, as, owing to its small overall height, it can be introduced through the relatively narrow hatches into the holds, where, owing to the great span of the jaws, it automatically grabs even the material lying under the gangways of the ships and not within reach of the grabs hitherto used. The new grab has the further advantage that during the first half of the closing operation the buckets, owing to the toggle action of the pressure bars, dig themselves firmly into the material independently of one another, while in the second half of the clos-

ing operation the material seized is shovelled up, the grab closing rapidly.

In the accompanying drawings a constructional example of the new grab is illustrated.

Figure 1 shows the closed grab in front elevation, only the guiding means of the discharging ropes being shown.

Figure 2 shows the pulley box with the guiding means for the discharging rope when the grab is open.

Figure 3 shows the grab when open, only the guiding means of the closing ropes being shown.

Figure 4 shows the pulley box with the guiding means for the loading or closing ropes when the grab is closed.

Figure 5 is a side elevation of the closed grab partly in section.

The grab consists of a rigid pulley box *a* on which the pressure bars *c*, *c'* are pivoted about points *b*, *b'*. The other end of the pressure bars are pivotally attached to the buckets *L*, *L'*. Laterally of the buckets and connected rigidly with them are arms *l*, *l'* which extend into the pulley box *a* in which they are movable independently of one another. For this purpose the ends of the arms of each bucket are connected together by a transverse shaft *e*, *e'* the free ends of which are provided with rollers *f*, *f'* which suitably engage in cam grooves *g*, *g'* provided on the pulley box. The latter are bent from pairs of angle irons. The ends of the bucket arms *l*, *l'* can therefore move in these cam grooves *g*, *g'* independently of one another.

The cam grooves *g*, *g'* for the shafts *e*, *e'* are preferably so shaped that they extend in the first place from the outside inwardly in a horizontal direction or at a slight inclination, after which they rise in the lifting direction. The shape of the cam groove varies according to the purpose for which the grab is to be used and the material to be dealt with, so as to obtain a suitable line of engagement. The engagement is further considerably assisted by the fact that the pivots *b*, *b'* and the pressure bars *c*, *c'* in the pulley box *a* are spread out as far as possible, and with a suitable construction of the cam grooves *g*, *g'*, a correspondingly wide span of the opened grab.

is obtained and that the pressure bars act as toggles and make the buckets penetrate more readily into the material.

For opening and closing the grab two discharging ropes m, m' and two closing ropes 5 (loading ropes) n, n' are employed. For the sake of clearness in Figures 1 and 2 only the rope guide for the discharging ropes and in Figures 3 and 4 only the rope guides for the closing ropes are shown. The two discharging ropes m, m' are led in a symmetrical arrangement (Figures 1 and 2) in series over guiding pulleys o, o' over pulleys h, h' and then round pulleys d, d' and their ends are secured at s and s' in the pulley box a . The 15 pulleys o, o' and h, h' are mounted rigidly on the pulley box a while the pulleys d, d' are rotatably mounted on the movable axles e, e' . All the pulleys of the discharging ropes thus lie in one plane, as is shown in Figure 5, in which, for the sake of simplicity, the pulley h' is omitted. In the arrangement shown the discharge ropes m, m' which are secured to the pulley box, together with the pairs of pulleys h, d and h', d' form pulley 25 block arrangements. When the ropes m, m' are pulled these cause the axles e or e' to be displaced outwardly and downwardly in the guides g, g' from the upper position shown in Fig. 1 (Fig. 2), the movement being limited 30 by stops t, t' (only shown in Fig. 4) on the pulleys f, f' . In this position the buckets L, L' take up the open position shown in Fig. 3.

The loading ropes n, n' coming from the crane cause the closing of the grab. These 35 are guided in a symmetrical arrangement (Figs. 3 and 4) over guide pulleys p, p' mounted rigidly on the pulley box a to the groups of pulleys D, D' mounted on the movable axles e, e' . The ropes pass over the 40 two innermost pulleys D, D' each to a group of pulleys k or k' rotatable about a fixed shaft K in the pulley box a . After two further turns round the pulleys D, k or D', k' , the ends of the loading ropes are crossed 45 over and secured to the oppositely disposed axles e' or e . In Fig. 5 the guide pulley p lies behind the innermost pulley k and the guide pulley p' in front of the innermost rope pulley k' . For the sake of simplicity the guide pulley p' has been omitted in Fig. 5. The loading ropes n, n' together with the groups of pulleys k, D and k', D' form pulley 50 block arrangements. When these ropes are pulled the grab buckets L, L' are moved 55 from the open position shown in Fig. 3 into the closed position (Fig. 1) the pulley axles e, e' being displaced upwardly in the guides g, g' by the pulley block arrangements k, D, k', D' (Fig. 4). During the closing operation each bucket L, L' can be adjusted independently of the other, the buckets being forced into the material by the pressure bars e, e' acting in the manner of toggles. The 60 toggle action here is stronger, the further 65

the pivots b, b' are from the middle axis of the grab.

For re-opening the closed grab the discharging ropes m, m' are held fast and the load ropes n, n' eased off. The pull in the 70 ropes will then pull the shafts e, e' of the bucket arms L, L' through the intermediary of the pulley block arrangements formed by the pulleys h, d or h', d' in the cam grooves g, g' until the grab is open. During this 75 operation the cam grooves g, g' cause the grab to open uniformly.

What I claim is:

1. An automatic grab with a large span having a pulley box, grab buckets, connecting rods joining the grab buckets to the pulley box, lateral pressure bars rigidly secured to the buckets, transverse axles connecting the free ends of the pressure bars, these free ends projecting into the pulley 80 box, cam grooves arranged in the pulley box, in which the ends of the pressure bars are guided, pulleys on the movable axles, pulleys in the pulley box, and ropes between the 85 pulleys on the movable axle and the pulleys in the pulley box for opening and closing each bucket independently.

2. An automatic grab as claimed in claim 1 in which the rigid pressure bars of each bucket are independently guided in the cam 90 grooves in the pulley box.

3. An automatic grab as claimed in claim 1 having discharging ropes adapted to form a pulley block arrangement between the ends of the bucket arms and a point on the pulley 100 box.

4. An automatic grab as claimed in claim 1 in which the cam grooves are smooth and curved.

In testimony whereof I have signed my 105 name to this specification.

HEINRICH REICHMANN.
